(57) **CLAIM**

The ornamental design for a short throw projector mount, as shown and described.

DESCRIPTION

FIG. 1 is a front perspective view of a short throw projector mount according to the invention;

FIG. 2 is a front elevation view of the short throw projector mount depicted in FIG. 1;

FIG. 3 is a side elevation view of the short throw projector mount depicted in FIG. 1;

FIG. 4 is an opposing side elevation view of the short throw projector mount depicted in FIG. 1;

FIG. 5 is a top plan view of the short throw projector mount depicted in FIG. 1; and,

FIG. 6 is a bottom plan view of the short throw projector mount depicted in FIG. 1.

The rear elevation of the depicted mount is not claimed, and hence is not depicted.

The broken line showing portions of a short throw projector mount is included for the purpose of illustrating environmental structure and forms no part of the claimed design.
